Application May 19, 1936, Serial No. 80,572

5 Claims. (Cl. 112—2)

- This invention relates to improvements in stitchers, having to do particularly with machines for stitching a longitudinal seam in a web or a series of superposed webs traveling at a constant rate of speed. The invention also relates to multiple forms in strips sewed together and weakened along transverse lines between adjacent forms both as to the strips themselves and as to the line of stitching.
- 5 10 It has become a relatively common procedure to produce multiple thickness forms in strips, the assemblage of the strips being perforated transversely at regular intervals along the division lines between forms, and being folded along the 15 perforation lines into accordion folds for convenience in handling and use. As a rule carbon paper is interposed between successive paper strips in order to transfer to the lower sheets any notations made on the top sheets.
- 20 The individual strips are frequently made up by putting longitudinal folds into relatively wide webs of paper, usually along scored lines. This procedure and the printing of the paper before the folding is done together result in what, for 25 lack of a better term, might be described as more or less fullness. The carbon paper is taken from rolls of the proper width and caused to enter the assemblage as the printed paper and carbon strips together are drawn along by a feeder which tightly 30 grips the assemblage and draws it along at a constant rate of speed. The carbon paper contains no fullness. Hence there has been considerable trouble heretofore in the operation of these machines because it has been necessary to stop 35 the machines at frequent intervals and increase the feed of carbon paper to compensate for the accumulated fullness in the paper strips.
- One of the objects of the present invention is to overcome the difficulties just mentioned by the 40 provision of a machine for stitching a longitudinal seam through the assemblage of strips, thereby holding them together while leaving them perfectly flexible so that they may be used in a typewriter or other machine of that general 45 character.
- Another object is the provision of a new mounting and drive for a sewing machine, adapting the same particularly for work of the character stated.
- 50 Other objects and features of novelty will appear as we proceed with the description of those embodiments of the invention which, for the purposes of the present application, we have illustrated in the accompanying drawings, in which
- 55 Fig. 1 is a side elevational view of a fragment of

a feeding machine or puller with our new sewing machine attached thereto.

Fig. 2 is a vertical transverse sectional view of the sewing machine taken substantially on the line 2—2 of Fig. 1.

Fig. 3 is a plan view partially in section on the line 3—3 of Fig. 1.

Fig. 4 is a top plan view of a fragment of a multiple form assemblage produced in accordance with the present invention.

Fig. 5 is a bottom plan view of the same.

Fig. 6 is a diagrammatic view illustrating the chain stitch resulting from the use of the machine.

Fig. 7 is a transverse sectional view taken substantially on the line 7—7 of Fig. 4.

In the drawings the frame of a puller or feeder is represented generally by the reference numeral 10. The puller consists of a pair of endless chains or belts 11 and 12 which travel over sprockets or wheels 13 and 14 at one end of the machine and corresponding sprockets or wheels (not shown) at the opposite end thereof. At regular intervals these chains or belts carry transverse gripping bars 15, those of the lower set of chains being arranged to cooperate with those of the upper set so as to grip the assemblage of strips between them and pull the same forward. Mechanism for perforating the strips transversely is located beyond the puller and is not herein illustrated being of more or less conventional form.

The drive for the puller may consist of a belt 16 driven from any suitable prime mover and running over a pulley 17. At its hub this pulley has a pinion 18 rigidly secured thereto. The pulley and pinion revolve together upon an extension of shaft 19, the latter being the shaft upon which sprockets or wheels 13 are keyed. Pinion 18 meshes with a large gear 20 which is keyed to shaft 21 upon which the sprockets or wheels 14 are secured. Outside of the frame on the opposite side of the puller the shafts 19 and 21 have keyed thereto intermeshing gears 22 and 23 of the same size. By this means the drive for the lower chain is transmitted from shaft 19 to shaft 21. The two sets of chains 11 and 12 therefore run at the same speed.

An idler gear 24 meshing with gear 23 is mounted to turn on a stub shaft 25 carried by the frame 10, and this gear in turn meshes with a gear 26 that turns on a stub shaft 27 carried by the frame 10. The ends of a further shaft 28 are mounted to turn in arms 29 extending forwardly from the frame, only one such arm being illustrated in the drawings. Fixed upon shaft 28 there

is a gear 30 which meshes with idler 26. The shaft 28 therefore rotates continuously whenever the puller is in operation.

Extended across the forward end of the puller frame 10 there is a metal plate 31 in which are formed two horizontal slots 32. On this plate 31 there is a transversely adjustable bracket 33 provided with forwardly extending rigid arms 34. This bracket is bored to receive bolts 34' or the like which engage the slots 32 and serve to hold the bracket in adjusted position upon the plate 31. The bracket 33 also carries an upwardly extending arm 35 in the upper end of which is mounted a pivot pin 36.

The bracket plate 33 also carries an approximately triangular forwardly extending plate 37 which serves to support certain gears. The shaft 28 extends loosely through this plate. Adjacent the plate 37 a large gear 38 is slidably keyed to the shaft 28 and is adapted to be moved lengthwise of the shaft whenever the bracket 33 and the plate 37 are adjusted transversely of the machine. The plate 37 carries a stub shaft 39 upon which is mounted a gear 40 meshing with gear 38. Gear 40 in turn meshes with the gear 41 which is likewise mounted upon a stub shaft 42 supported by the plate 37. Hence the gear 41 is rotated at constant speed from shaft 28 regardless of the position of adjustment of the transversely movable bracket and its accompanying parts.

The forwardly projecting arms 34, which are movable with the bracket 33, are joined at their forward extremities by shaft 43 upon which are oscillatably mounted two legs 44 that are joined at their upper ends by a small table 45. The legs 44 and table 45 in the present instance form a part of the frame of the sewing machine which oscillates bodily about the shaft or pivot 43. The machine proper comprises a base 46 which is secured to the table 45 by bolts 47 or the like, providing for removal to permit servicing or replacement.

Near one end of the base 46 there is secured an upwardly extending post 48. This post is bored and counterbored to receive a ball bearing 49. At the opposite end of the base there is mounted a housing 50 for a ball bearing 51, with an upwardly projecting standard 52 rigidly connected with the housing 50. A transverse brace 53 connects the upper end of standard 52 with post 48.

In the bearings 49 and 51 is mounted the principal shaft 54 of the sewing machine. This shaft on one end carries a looper 55 of conventional form. At the opposite end of the shaft there is keyed a gear 56 which meshes with gear 41. On the shaft 54 just inside of the gear 56 there is secured an eccentric sleeve 57 upon which is mounted a ball bearing 58 so designed as to provide a small universal joint action. On the outer race of this bearing there is mounted a ring 59 having a threaded socket in which is adjustably threaded a rod 60. A small universal joint 61 with anti-friction bearings is carried in the upper end of rod 60, and by this means connection is had with one extremity of a lever 62 pivoted at 63 upon the brace 53.

Attached to post 48 and projecting laterally therefrom are two guide blocks 64 and 65 having aligned bores within which the needle bar 66 slides. The needle bar is reciprocated by a short link 67 pivotally connected with the needle bar and with the free extremity of lever 62. A second bar 68 is also mounted in the blocks 64 and

65 and carries a spring metal foot 69, provided with an opening through which the needle 18 is adapted to project when it descends and enters the work. The bar 68 is held against rotational movement by a stud 71 loosely engaging a flattened part of the bar. Coil spring 72 interposed between the block 64 and a collar 73 on the bar tends to depress the same. Working against this spring however there is a nut 74 threaded upon the upper end of the bar and bearing against the top of block 64, this nut being provided with a serrated disk portion 75 which is engaged by a spring detent 76, by which it is held against accidental movement. 77 is a metal plate over which the work is adapted to be fed, and in which there is an opening 78 for the needle.

We mount a second eccentric sleeve 79 on shaft 54. This sleeve carries the inner race of a ball bearing 80, the outer race of which is received within a large opening in one end of an oscillating stay link 81. The opposite end of this link is mounted upon the fixed pivot 36. It will be obvious that as the eccentric 79 rotates with the shaft 54, the engagement of the eccentric within the circular opening in link 81 will cause the pivoted frame of the sewing machine to swing back and forth upon the pivot shaft 43. The eccentricity of the sleeve 79 is not sufficient to produce a very great movement of the machine at the needle height, and the extent of this movement may of course be varied by substituting sleeves of different eccentricity. The parts are so arranged and timed that the forward movement of the needle takes place during the lower portion of its stroke when it is in engagement with the work, and at approximately the same speed as that of the work, while the return movement takes place when the needle is in the upper portion of its stroke and out of engagement with the work. We have found that good results are obtained by the use of a stitch one-third inch long, which means that the shaft 54 makes three complete revolutions for each inch of travel of the work.

In order to support the strips while they are being fed through the machine we mount a thin metal plate 82 on the frame 10 of the puller in any suitable manner, the surface of this plate being preferably slightly below that of the small plate 77 which is attached to and moves with the sewing machine frame. The plate 82 extends forward to approximately the position indicated in Fig. 1, where it will just clear the path of the clamping bars 15 as they move with the chains 11 and 12. A post 9, attached to the brace 53, carries a thread tensioner of any known construction, through which extends the cotton thread T used in stitching the strips together.

The operation of the machine, it is believed, will be obvious from the foregoing description of its construction, it being borne in mind that the entire sewing machine oscillates back and forth in timed relation to the reciprocations of the needle, and that the assemblage of paper strips and carbon strips is drawn through the sewing machine at a constant rate of speed by the puller with its gripping bars 15. When the machine is in the center of its oscillation, the meshing relation between gears 41 and 56 is close, whereas it is loosened slightly as the frame approaches the end of its stroke in either direction. However, the distance between the pivot shaft 43 and the point of engagement of the gears is sufficiently great so that the functioning of the gears is not materially affected by the

oscillations of the frame. The position of the line of stitching may be varied as desired by movement of the bracket plate 33 transversely, and the machine may be built as a left-hand 5 stitcher, as shown herein, or as a right-hand stitcher, when the arrangement of the parts would be largely reversed. Of course it will be apparent that instead of the eccentric 79 and link 81 herein illustrated, we may use a crank 10 and connecting rod, the crank being in effect a form of eccentric.

In Figs. 4, 5 and 7 we have shown a fragment of a multiple form constructed in accordance with the invention. The paper strips P are 15 shown as folded along one edge, which may or may not be the case, and the carbon strips C are interleaved with the paper strips. A longitudinal line of perforations 90 may be employed if desired, and these perforations may extend through 20 the assembly or through the paper strips only, as preferred. At regular intervals, dividing the assembled strips into multiple form units, there are transverse lines of perforations 91 also extending through the complete assemblage. The transverse perforations are put into the assemblage of strips after the stitches which are illustrated in the drawings at S are completed.

In order that the various units of the forms may be easily detached when required, we cut 30 the thread of the seam at the points where the lines of transverse perforations intersect the line of stitching. Preferably this cutting is done on the upper side only of the strip assemblage at the point 92, as indicated in Fig. 4, the stitching 35 on the lower side being intact, as shown in Fig. 5. A chain stitch being used, the cutting of the single thread in one place is sufficient if the unit to be removed is given a quick snap. On the other hand the stitching is not loosened by 40 the single cut to the extent to which it would be if the looped thread on the bottom of the assemblage was also cut, and hence the seam remains effective through all of the necessary handling of the forms.

Having thus described our invention, we claim: 45
 1. In a sewing machine for use with material fed at a constant rate of travel, a driving gear, a fixed bearing therefor, a frame for the machine bodily movable back and forth in the direction of feed of said material, a transverse shaft journaled in said frame, a gear on said shaft meshing 50 with said first named gear by which said shaft is rotated, needle reciprocating means driven from said shaft, and means actuated by the rotation of said shaft for moving said machine back and forth in timed relation to the reciprocations of the needle, the gear on the machine riding over the periphery of the first named gear for a short distance on either side 55 of the plane joining their axes when the machine is in its middle position.

2. In apparatus for making multiple forms in superposed strips, means for feeding the strips lengthwise at a constant rate of travel, a frame, 60 mechanism for oscillating the frame backward and forward, the forward oscillation corresponding in speed substantially with the speed of forward travel of the strips, a sewing machine

mounted on said frame and operated in synchronism with the movements of oscillation of the frame, the needle of the sewing machine entering the work during the forward oscillation only of the frame, whereby a longitudinal seam 5 is sewn through the superposed strips during the constant rate travel thereof, and means for moving the frame transversely to different positions of adjustment without disturbing the drive to the oscillating mechanism and sewing machine 10 mechanism.

3. In combination, a frame, means thereon for feeding a web of material at a constant rate of travel, a sewing machine for stitching a longitudinal seam in the web, said machine being 15 mounted for bodily movement on the frame backward and forward with respect to the line of travel of the web, and means timed with the reciprocations of the machine needle for effecting said bodily movement of the machine to provide forward movement when the needle is in the web and rearward movement when the needle is out of the web, said bodily movement mechanism and said stitching mechanism being connected with said web feeding mechanism by 25 non-slip driving connections, said connections comprising a gear on the frame mounted to turn upon a fixed axis, and a gear on the machine meshing with said first named gear and having a limited movement backward and forward with 30 respect to the direction of movement of the teeth of the first named gear.

4. In combination, a frame, means thereon for feeding a web of material at a constant rate of travel, a sewing machine comprising mechanism 35 for stitching a longitudinal seam in the web, said machine being pivotally mounted on the frame to swing back and forth with respect to the line of travel of the web, means timed with the reciprocations of the machine needle for effecting 40 said swinging movement to provide forward movement when the needle is in the web and rearward movement when the needle is out of the web, said machine swinging mechanism and said stitching mechanism being operatively connected with said web feeding mechanism by 45 means comprising a gear on the frame mounted to turn upon a fixed axis, and a gear on the machine meshing with said first named gear and having a limited movement back and forth over 50 said first named gear.

5. In combination, a frame, means thereon for feeding a web of material lengthwise of the frame at a constant rate of travel, a sewing machine for stitching a longitudinal seam in the 55 web, said machine comprising a horizontal drive shaft, an upright arm carrying said machine, said arm being mounted at its lower end upon a pivot extending transversely of the frame, means cooperating with said drive shaft for swinging 60 said arm back and forth upon its pivot, a gear on said shaft, a gear meshing with said shaft gear and located on the frame between the shaft gear and the arm pivot, and driving connections interposed between said frame gear and said web 65 feeding means.
